(57) **CLAIM**

The ornamental design for a floatation device, as shown as described.

DESCRIPTION

FIG. 1 is a front side perspective view of my floatation device;
FIG. 2 is a front elevation view thereof;
FIG. 3 is a rear elevation view thereof;
FIG. 4 is a left side elevation view thereof;
FIG. 5 is a right side elevation view thereof;
FIG. 6 is a top plan view thereof;
FIG. 7 is a bottom plan view thereof; and,
FIG. 8 is a front side perspective view thereof in an open configuration.

The broken line showing is for illustrative purposes only and forms no part of the claimed design.
